UNITED STATES PATENT OFFICE.

WILLIAM J. McNALLY, OF FRAMINGHAM, MASSACHUSETTS, ASSIGNOR TO DENNISON MANUFACTURING COMPANY, OF FRAMINGHAM, MASSACHUSETTS, A CORPORATION OF MASSACHUSETTS.

GAME COUNTER AND PROCESS OF MAKING THE SAME.

Application filed June 24, 1927. Serial No. 201,135.

This invention relates to game counters, such as poker chips and the like, and to a method of making the same and has for its principal object the provision of a game counter which may be easily and economically manufactured from inexpensive materials, yet which will be durable in use, light in weight and attractive in appearance.

Heretofore poker chips have usually been made of ivory, bone, composition substances or laminated bristol board, and have been generally satisfactory in use. All of these materials are, however, more or less expensive and, as the formation of disc-like chips involves considerable waste of material the cost of manufacture necessitates a high selling price of the products. In order to reduce the manufacturing cost of these articles, I have devised a method of making poker chips of news board which, as is well known, is considerably cheaper than bristol board and much less expensive than ivory or bone. The process preferably consists in applying a paper sheet to each surface of a strip of news board, cutting disc-like portions from the strip, pressing the discs thereby rounding their peripheral edges, and building up the composite edge with a composition of vegetable wax.

In the accompanying drawings which illustrate the several steps in the process and show a recommended form of the improved article,

Fig. 1 is a perspective view of a sheet of news board having a paper strip applied to each surface;

Fig. 2 is a plan view of the sheet after several discs have been cut out;

Fig. 3 shows a plan view and an edge view of one of the cut-out discs;

Fig. 4 is an enlarged diametrical section through a disc after the pressing operation;

Fig. 5 is a similar view after the application of the wax; and

Fig. 6 is a plan view of the completed counter.

The several steps of the process may readily be performed by hand operations or by suitable machinery. Preferably, the news board sheet 7, of suitable thickness, is mechanically stripped on both sides with thin paper sheets 8 and 9, a suitable adhesive uniting the paper to the body; the discs 10 are died out and pressed by appropriate ma-

chines; and the periphery of the discs is built up into rounded edges by the application of a rapidly solidifying, molten vegetable wax 11. The edge may, if desired, be buffed or frictionally polished.

It will be noted from Figs. 4 and 5 that the pressing operation tends to round the peripheral edges of the discs, as at 12, and that the wax 11 covers the edges of the paper strips 8 and 9. By providing paper sheets of the appropriate color and by coloring the wax correspondingly, the resulting poker chip will have smooth surfaces and rounded edges of substantially the same texture and tint, and will simulate very closely the appearance of a bone or ivory counter. It will be found that the wax edge adheres so closely to the periphery of the disc that the circumferential line of union, as at 13, is scarcely distinguishable.

Game counters constructed as aforesaid are substantially as wear-resisting in use as those heretofore provided and will not break as readily as bone chips, yet they may be manufactured in quantity at slight cost and sold at a low price. It will be understood, however, that details of structure may be varied or changes in the steps of the process of manufacture may be practiced without departing from the essence of the invention as defined in the following claims.

I claim:

1. A game counter consisting of a body portion of sheet material and a paper strip applied upon each surface of said sheet, and having a peripheral edge of wax-like material.

2. A game counter consisting of a body portion of sheet material and a paper strip applied upon each surface of the news board, and having a rounded peripheral edge of wax-like material.

3. A game counter comprising a disc body of sheet material, a paper disc applied upon each surface of the disc body, the peripheries of the disc body and paper discs substantially registering with each other, and a rounded edge of wax-like material, said material extending over the peripheral edges of the paper discs.

4. A process of making game counters including as steps applying paper strips to the front and back surfaces of a sheet, cutting a disc from the sheet, and building up the pe-

riphery of the disc with a wax-like substance.

5. A process of making game counters including as steps applying paper strips to the front and back surfaces of a sheet, cutting a disc from the sheet, pressing the disc and rounding the peripheral edges thereof, and building up the periphery of the disc with a wax-like substance.

6. A process of making game counters including as steps adhesively applying paper

strips to the front and back surfaces of a sheet, cutting a disc from the sheet, pressing the disc and rounding the peripheral edges thereof, applying a wax-like substance to the edge of the disc and over said rounded edges, 15 and rounding the resulting edge.

Signed by me at Framingham, Massachusetts, this twentieth day of June, 1927.

WILLIAM J. McNALLY.
